UNITED STATES PATENT OFFICE.

JOSEPH PATCHETT, OF LAWRENCE, MASSACHUSETTS.

VENTILATOR.

SPECIFICATION forming part of Letters Patent No. 248,207, dated October 11, 1881.

Application filed April 22, 1881. (Model.)

To all whom it may concern:

Be it known that I, JOSEPH PATCHETT, of Lawrence, in the county of Essex and State of Massachusetts, have invented a new and Improved Ventilator, of which the following is a specification.

Figure 1 is a plan view of my invention with the cover removed. Fig. 2 is a vertical section of my invention taken partly through the middle line of the inlet-flue and partly through the top immediately above the mouth of the outlet-flue. Fig. 3 is also a vertical cross-section taken on the line $y y$ of Fig. 1; and Fig. 4 is a horizontal section taken on the line $z z$ of Figs. 2 and 3.

Similar letters of reference indicate corresponding parts.

A represents the air-inlet flue and B the air-outlet flue. The top or outer opening of the air-outlet flue is on a higher level than that of the inlet-flue, and opens immediately under the cover C. The top of the air-inlet flue is covered over, as shown at b, but receives the air through the side openings, c, and the outer end or top of this flue is provided above the opening c with the deflecting flange a and below with the flange a', which is provided with the perforations a''. These flanges may surround the upper ends of both flues, if desired. The object of this construction of the flues is to give to the outgoing current as direct a course as possible, and provide a circuitous passage for the incoming current.

Surrounding the top of the flues is secured the rim D, which may have the ornamentation d secured to or formed upon it. This rim is secured a small distance from the upper ends of the flues by means of the plates or studs e e, which are secured at intervals to the flues and the inside of the rim, and which are cut away at the top to form a seat for the cover C, which is of such size relative to the size of the flues that when in place the edge i thereof will come to a line about midway between the outer edge of the flues and the rim D, thus forming the passage b for the outgoing air.

When intended for use in windows or similar places the flues should be curved or turned backward, and have the form as shown in the drawings, so that the ends thereof will reach past the frame and sash of the window, and the device should be provided with the ex-

tended back plate, E, for securing the same in proper position to the outside of the building; but it is obvious that this form or external shape and means of attachment of the ventilator are not essential, nor indeed is any particular form necessary, as the same may be modified to suit the various localities in which it is to be attached to the building or room and not depart from the spirit of my invention.

By the use of a ventilator thus constructed the vitiated air of a room or building will be rapidly replaced by the external air without creating cold current or drafts through the room or building, which are so dangerous to health.

Having thus fully described my invention, I claim as new, and desire to secure by Letters Patent—

1. In a ventilator, the outlet-flue B, in combination with the inlet-flue A, the inlet-flue being covered at the top and formed with the side opening, c, substantially as and for the purposes specified.

2. In a ventilator, the outlet-flue B, in combination with the inlet-flue A, the top or outer opening of the outlet-flue being on a higher level than the side opening of the inlet-flue, substantially as and for the purposes specified.

3. The outlet-flue B and the covered inlet-flue A, in combination with the rim D and the cover C, substantially as and for the purposes specified.

4. The outlet-flue B and the covered inlet-flue A, formed with the side opening, c, and provided with the deflector a and the perforated flange a', in combination with the rim D, substantially as and for the purposes specified.

5. The outlet-flue B and the inlet-flue A, formed with the opening c, in combination with the flue h, formed by the cover C and the rim D, substantially as and for the purposes specified.

6. The herein-described ventilator, consisting of the inlet-flue A, cap b, opening c, flanges a a', perforations a'', rim D, plates e, cover C, passage h, and outlet-flue B, substantially as and for the purposes specified.

JOSEPH PATCHETT.
